(57) **CLAIM**

The ornamental design for cradle for electronic computer, as shown and described.

DESCRIPTION

FIG. 1 is a perspective view of cradle for electronic computer showing my new design,

FIG. 2 is a front elevational view thereof,

FIG. 3 is a rear elevational view thereof,

FIG. 4 is a left side elevational view thereof,

FIG. 5 is a right side elevational view thereof,

FIG. 6 is a top plan view thereof,

FIG. 7 is a bottom plan view thereof,

FIG. 8 is an enlarged sectional view taken along line 8-8 with internal mechanism being omitted thereof,

FIG. 9 is a front elevational view showing the article in a closed position thereof,

FIG. 10 is a right side elevational view showing the article in the closed position thereof; and,

FIG. 11 is a top plan view showing the article in the closed position thereof.

The broken line showing of the "cradle for electric computer" is included for the purpose of illustrating the environment of the claimed design and forms no part thereof.

1 Claim, 8 Drawing Sheets
